United States Patent

Des. 239,596
Patented Apr. 20, 1976

239,596

PACKAGING CONTAINER OR SIMILAR ARTICLE

Amilcare Dogliotti, Neive, Italy, assignor to P. Ferrero
& C. S.p.A., Alba, Cuneo, Italy

Filed Oct. 31, 1973, Ser. No. 411,566

Term of patent 14 years

Int. Cl. D9—01

U.S. Cl. D9—174

FIG. 1

FIG. 2

FIG. 4

FIG. 1 is a perspective view of a packaging container or similar article, showing my new design;

FIG. 2 is a top plan view, the bottom being the same in appearance;

FIG. 3 is a front elevational view; and

FIG. 4 is a side elevational view thereof.

I claim:

The ornamental design for a packaging container or similar article, as shown.
